HEATER

Harry H. Fleer, Quincy, Ill., assignor to Gem City Pattern Co., Quincy, Ill., a corporation of Illinois

Application January 4, 1943, Serial No. 471,234

8 Claims. (Cl. 126—77)

1

My invention relates, generally, to heaters and it has particular relation to heaters of the warm air type for heating space by radiation and convection.

An object of my invention is to provide for introducing primary air into the fire box around the outside of the fire bed so as to cause the fuel to burn from the outside inwardly.

Another object of my invention is to provide for distributing the primary air to the rifling or spiral grooves in the inner surface of the fire box which in turn distribute it around the outside of the fire bed.

A further object of my invention is to provide for distributing the secondary air around the fire box and into the upper portion thereof.

Still another object of my invention is to so arrange and construct the fire box and the rifling or spiral grooves therein that the ashes from the fuel bed will tend to flow downwardly into the ash pit.

Other objects of my invention will, in part, be obvious and in part appear hereinafter.

For a more complete understanding of the nature and scope of my invention reference may be had to the following detailed description taken in connection with the accompanying drawings in which:

Figure 1 is a perspective view of a preferred form of heater in which the present invention is incorporated;

Figure 2 is a vertical sectional view taken along the line 2—2 of Figure 4 and showing the internal details of construction of the heater shown in Figure 1 and the paths of the primary and secondary air;

Figure 3 is a detail sectional view taken on the line 3—3 of Figure 2;

Figure 4 is a detail sectional view taken on the line 4—4 of Figure 2; and

Figure 5 is a detail sectional view taken along the line 5—5 of Figure 4.

Referring now particularly to Figure 1 of the drawings, it will be observed that the reference character 10 designates, generally, a heater in which the present invention is incorporated. The heater 10 is provided with a casing or drum 11, preferably of sheet steel, which may be supported at its lower end on legs 12. At the upper end there is provided a stack 13 to which the conventional stove pipe can be attached for carrying away the gases incident to combustion. A cap or cover 14 is provided at the upper end of the heater 10 which includes a door 15 having a handle 16 for opening the same. It is intended that the fuel for the heater 10 shall be fed to the fire box through the aperture closed by the door 15. Projecting through the door 15 is a handle 17 which is attached to a slide 18, Figure 2, for closing apertures 19 in the cover 14. Ad-

2

ditional secondary air can be admitted through the apertures 19, if desired.

The primary air can be admitted through apertures 20 and control of the same is provided by means of a handle 21 attached to a slide 22, Figure 2 of the drawings. As will be set forth hereinafter, the primary air through the apertures 20 is caused to flow around the fuel bed so as to permit combustion around the same.

10 At the lower portion of the heater 10 there is provided a door 25 which can be opened to remove ashes from the ash pit. The door 25 is provided with an auxiliary door 26 which can be opened to permit access to the ash pit for shaking the grate in a conventional manner.

15 Referring now particularly to Figures 2, 3 and 4 of the drawings, it will be observed that a liner 30 of suitable refractory material, such as fire brick or tile, is provided inside of the casing or steel drum 11. As shown in Figure 5 this liner 30, which is made up of several pieces 31 of fire brick or tile, is in contact engagement with the inner surface of the casing or steel drum 11, except for certain portions thereof as will be set forth hereinafter. It has been found that this construction with the casing or steel drum 11 in contact with the liner 30 for the major portion of its extent materially increases the efficiency of the heater 10.

20 As shown in Figures 3 and 4 of the drawings, the liner 30 can be made up of eight sections or pieces 31 of fire brick or tile. Obviously, a greater or smaller number can be employed if desired. The sections 31 are arranged to form a generally cylindrical fire box 32 the longitudinal axis of which is vertical as illustrated. Preferably, the diameter, as indicated by the broken line 33 of Figure 2, at the upper end of the fire box 32 is slightly smaller than the diameter, indicated by the broken line 34, at the lower end so that a generally conical construction is provided which tapers outwardly and downwardly to facilitate the flow of ashes from the fuel bed in the fire box 32 to the ash pit therebelow.

25 Now it is desirable to have the fuel bed burn from the outside inwardly rather than to burn from the inside outwardly. A much more efficient combustion is obtained and generally the heater 10 is much more efficient if the combustion is of this character. In order to effect this desirable result the primary air is directed so that it flows around the outside of the fuel bed. For this purpose the inner surface of the fire box 32 is rifled or provided with spiral grooves 37 through which the primary air can flow. The lower end of each of the grooves 37 extends vertically downwardly as indicated at 38.

30 With a view to preventing the spiral grooves 37 from being clogged with ashes from the fuel bed, the upper edge of each of the grooves, as

indicated at 39, extends generally horizontally or substantially at right angles to the vertical axis of the fire box 32. The lower side 40 of each of the spiral grooves 37 slopes downwardly, as shown, so that the ashes therein tend to flow downwardly toward the fire box.

The liner 30 made up of the sections 31 of fire brick or tile is supported at the lower end by a lower clamp ring 42 which is provided with apertures 43 registering with the vertical grooves 38 in which the lower ends of the spiral grooves 37 open as previously described. The lower clamp ring 42 extends into the fire box 32 and has integrally formed therewith a flange 44 which interfits with the lower inner surface of the liner 30 and slopes so as to facilitate the flow of ashes to the ash pit.

Underneath the lower clamp ring 42 and supporting the same is a grate ring 45 which, together with the clamp ring 42, provides an annular passageway or channel 46 through which the primary air, as indicated by the arrows 47, can be distributed from the openings 20 to the spiral grooves 37. It will be understood that the annular passageway or channel 46 extends entirely around the lower end of the liner 30 and that it is common to all of the grooves 38.

Integrally formed with the grate ring 45 is a flange 48 which is inclined to form a continuation of the flange 44 for directing the flow of ashes to the ash pit. Grooves 49, registering with the apertures 43 and grooves 38, are provided to facilitate the flow of ashes therefrom to the ash pit.

The grate ring 45 is provided with a plurality of integrally formed ears 50, Figure 4, for supporting an auxiliary grate ring 51, Figure 2, which in turn supports a conventional grate 52.

Since the grooves 49 in the grate ring 45 will normally be filled with ashes, substantially none of the primary air will flow therethrough. It follows that the entire supply of primary air will flow through the lower channel or annular passageway 46 and be distributed to the grooves 38 and thence through the spiral grooves 37 for supporting combustion at the outside of the fuel bed and causing the fuel bed to burn from the outside inwardly. That is, substantially no air can work its way through the grooves 49 and up through the center of the fuel bed since these grooves are normally filled with ashes. By causing the fuel bed to burn from the outside inwardly better combustion is obtained because the adjacent heated liner 30 helps to ignite the gases evolved from the fuel and the fuel burns completely away from the liner 30, thereby eliminating the tendency for the fuel bed to arch as is the case when it burns up through the center.

The grate ring 45 can be supported in any suitable manner such as by standards 53 projecting upwardly from the bottom of the ash pit 54.

The major portion of the secondary air is admitted through apertures 57 and the amount is controlled by a slide 58, Figure 4, having a projecting handle 59 for adjusting the same. The apertures 57 open into a channel 60, which is annular in character and which is formed in the lower end of the liner 30, as shown. The annular passageway 60 for the secondary air is common to vertically extending passageways 61 in the outside surface of the liner 30. Except for these passageways 61, the liner 30 is in contact engagement with the casing or steel drum 11, as previously described. At their upper ends the passageways 61 communicate with two sets of apertures 62 and 63 which extend through the

liner 30 and into the fire box 32 at the upper end, as indicated more clearly for apertures 63 in Figure 3 of the drawings. Apertures 62 are identical with apertures 63. If desired, one of the sets of apertures 62 or 63 can be omitted if it is found that sufficient secondary air is supplied by a single set.

The upper ends of the passageways 61 communicate with a passageway 64 that is annular in character and is formed by an upper clamp ring 65. The upper clamp ring 65 can be provided with apertures 66 through which the secondary air can also be distributed to the upper end of the fire box 32. If desired, either the apertures 66 or both sets of apertures 62 and 63 can be omitted or used depending upon the amount of secondary air that is required. Preferably the apertures 66 in the upper clamp ring 65 are omitted. Reliance is then placed on the apertures 62 and 63 to supply the necessary secondary air. It will be understood that additional apertures, such as the apertures 62 and 63 in the liner 30, can be employed, if desired.

The flow of the secondary air is indicated by the arrows 67. It will be observed that it enters through the apertures 57 near the rear of the heater 10 and that it flows through the annular passageway 60 and upwardly through the vertical passageways 61. It then flows through suitable apertures, as described, into the upper end of the fire box 32.

As shown in Figure 2 of the drawings, the upper clamp ring 65 is provided with suitable ears, one of which is indicated at 68, which rest upon the upper end of the liner 30. Recessed portions are provided in the upper clamp ring 65, as indicated at 69, to permit access to the stove bolt 70 which serves, together with other stove bolts, to hold the cap 14 in place on the upper end of the casing or steel drum 11.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

I claim as my invention:

1. In a heater, in combination, an upright casing, a liner for said casing of refractory material defining a fire box, the inner surface of said liner tapering downwardly and outwardly to facilitate the downward flow of ashes in the fire box, said inner surface having a plurality of primary air supply grooves extending upward from its lower end for directing the flow of primary air to the outside of the fuel bed in said fire box, a lower clamp ring underneath said liner for supporting the same, said clamp ring projecting into said fire box and having apertures therein registering with the lower ends of said grooves, a grate ring adapted to carry a grate below the fire box and supporting said lower clamp ring and cooperating therewith to provide a passageway common to said apertures and communicating with the outside of said casing for distributing primary air to said grooves, and an upper clamp ring at the upper end of said liner cooperating therewith to provide a circular passageway having apertures opening into the upper end of the fire box to direct the flow of secondary air thereto, said liner being provided with a plurality of vertically extending passageways communicating with said circular passageway for the flow of secondary air therethrough, and said liner being

provided with a passageway common to the lower ends of said vertical passageways and communicating with the outside of said casing for distributing secondary air to said passageways.

2. In a heater, a casing having an ash pit at its lower end, a grate ring mounted in said casing above said ash pit, a clamp ring mounted in said casing in superposed spaced relation to said grate ring, said rings having interfitting engagement at their inner portions, a refractory lining mounted on said clamp ring provided in its inner surface with primary air supply grooves extending upward from its lower end, said clamp ring having spaced openings therein in register with the lower ends of said grooves and said grate ring having ash receiving depressions underlying said openings and extending downward therefrom, said rings defining between them a primary air receiving space communicating at the upper ends of said depressions with said openings and otherwise closed to the ash pit, and means for admitting air to said space.

3. In a heater, a casing having an ash pit at its lower end, a grate ring mounted in said casing above said ash pit, a grate structure supported at the lower end of said ring in proximity thereto, a clamp ring mounted in said casing in superposed spaced relation to said grate ring, said rings having interfitting engagement at their inner portions, a refractory lining in said casing mounted on said clamp ring provided in its inner surface with primary air supply grooves extending upward from its lower end, said clamp ring having spaced openings therein in register with the lower ends of said grooves and said grate ring having ash receiving depressions therein underlying said openings and inclined downwardly and inwardly of said casing toward said grate structure, said rings defining between them a primary air receiving space communicating at the upper ends of said depressions with said openings and otherwise closed to the ash pit, and means for admitting air to said space.

4. In a heater, a casing having an ash pit at its lower end, a grate ring mounted in said casing above said ash pit, a grate structure supported at the lower end of said ring in proximity thereto, a clamp ring mounted in said casing in superposed spaced relation to said grate ring, said rings having interfitting engagement at their inner portions, a refractory lining in said casing mounted on said clamp ring provided in its inner surface with primary air supply grooves extending upward from its lower end and having their lower end portions straight and substantially vertical, said clamp ring having spaced openings therein in register with the lower ends of said grooves and said grate ring having ash receiving depressions therein underlying said openings and inclined downwardly and inwardly of said casing toward said grate structure, said rings defining between them a primary air receiving space communicating at the upper ends of said depressions with said openings and otherwise closed to the ash pit, and means for admitting air to said space.

5. In a heater, a casing having an ash pit at its lower end, a grate ring mounted in said casing above said ash pit, a clamp ring mounted in said casing in superposed spaced relation to said grate ring, said rings having interfitting engagement at their inner portions, a refractory lining mounted on said clamp ring provided in its inner surface with primary air supply grooves extending upward from its lower end, said clamp ring

having spaced openings therein in register with the lower ends of said grooves and said grate ring having ash receiving depressions underlying and extending downward from said openings, said rings defining between them a primary air receiving space communicating at the upper ends of said depressions with said openings and otherwise closed to the ash pit, said lining being spaced at its lower portion from said casing defining therewith and with said clamp ring a secondary air receiving space extending about said liner and closed to said primary air space and to said ash pit, said liner having in its outer face secondary air channels opening into said secondary air space, means for admitting air from outside of said casing to said primary air space, means for admitting air from outside of said casing to said secondary air space, and means for permitting secondary air from said channels to enter the combustion space of said heater.

6. In a heater, a casing having an ash pit at its lower end, a refractory lining in said casing above said ash pit provided in its inner surface with primary air supply grooves extending upward from its lower end, means providing a primary air receiving space extending about said casing above said ash pit and communicating with the lower ends of said grooves, means for admitting air to said space from the exterior of said casing and independently of said ash pit, means defining in cooperation with said casing and said liner a secondary air receiving space extending about the lower portion of said liner and closed to said primary air space and to said ash pit, said liner having in its outer face secondary air conducting channels opening into and extending upward from said secondary air space, means for admitting air to said secondary air space from outside of said casing and independently of said primary air space and of said ash pit, and means for permitting secondary air from said channels to enter the combustion space of said heater.

7. In a heater, a casing having an ash pit at its lower end, a refractory lining in said casing above said ash pit provided in its inner surface with primary air supply grooves extending upward from its lower end portion and having in its outer surface upwardly extending secondary air channels opening at their upper portions into the space defined by said lining, means for supplying to the lower ends of said grooves primary air from outside of said casing and ash pit, and means for supplying to the lower ends of said channels secondary air from the exterior of said casing independently of said primary air supply means and of said ash pit.

8. In a heater, a casing having an ash pit at its lower end, a grate ring mounted in said casing above said ash pit, a clamp ring mounted in said casing in superposed spaced relation to said grate ring, a refractory lining mounted on said clamp ring provided in its inner face with primary air supply grooves extending upward from its lower end, said rings defining between them a primary air receiving space communicating with the lower ends of said grooves, means for supplying primary air to said space from the exterior of said casing and ash pit, and means for supplying secondary air to the combustion space of said heater from the exterior of said casing and independently of said primary air supply means and of said ash pit.
